UNITED STATES PATENT OFFICE.

JOHN A. FRASER, OF BENTON HARBOR, MICHIGAN, ASSIGNEE TO FRANK M. VAWTER,
OF BENTON HARBOR, MICHIGAN, IN TRUST.

PRINTER'S FURNITURE.

1,071,150.

Specification of Letters Patent. Patented Aug. 26, 1913.

Application filed July 8, 1911. Serial No. 637,571.

To all whom it may concern:

Be it known that I, JOHN A. FRASER, a citizen of the United States, and resident of Benton Harbor, in the county of Berrien and State of Michigan, have invented certain new and useful Improvements in Printers' Furniture, of which the following is a full, clear, and exact specification.

This invention relates to improvements in printers' furniture, and particularly to fillers for use in filling up spaces in setting up and completing printers' forms heretofore produced by casting, and in some instances from two pieces of sheet steel, the 15 diaphragm being in one piece and the rim in another piece, the ends of the rim being secured by a dove tailed joint, and the diaphragm being provided with lugs projecting through perforations in the sides of the rim. 20 Cast fillers, when from soft metals, of which lead and its alloys are an example, are not capable of successfully withstanding the repeated compressions or forces to which they are necessarily subjected, and when of cast 25 iron are frequently broken owing to their brittleness, while on the other hand when a filler is made from two pieces of steel jointed together to form the rim and diaphragm, as above described, these compressions force 30 the joints apart, and in some instances deflect or bend the rim out of shape owing to its weakness due to the perforations therein and its tendency to rust on and break off the lugs projecting from the diaphragm 35 therethrough. Furthermore the dove tailed jointed ends of the rim involve a loss of metal and strength in the rim that it is desirable to avoid.

The object of my invention is printers' 40 furniture, and particularly a filler, composed of two pieces of sheet steel, each of which is provided with a diaphragm adapted to be conveniently and permanently secured one to the other by welding, soldering or riveting, and an otherwise jointless continuous 45 rim integral with the diaphragm, whereby a filler of maximum strength, resistance to pressure, durability and economy of construction may be produced and in the absence of waste metal in the formation of a 50 filler.

With these ends in view, my invention finds embodiment in certain features of novelty in the construction, combination and arrangement of parts by which the said ob-

jects and certain other objects are herein-
after attained, all as fully described with
reference to the accompanying drawings,
and more particularly pointed out in the
claims.

In said drawings:—Figure 1 illustrates,
in perspective, a filler embodying my invention.
Fig. 2 is a top plan view thereof.
Fig. 3 is a longitudinal section on the line
3—3 of Fig. 2. Fig. 4 is a transverse sec-
tion on the line 4—4 of Fig. 2; and, Fig.
5 is a plan view of a blank from which the
entire one half of a filler is formed.

Similar characters of reference indicate
the same parts in the several figures of the
drawings.

In carrying out my invention I first form
two blanks 6 from sheet steel, and by a bend-
ing and drawing process simultaneously
turn up the side and end portions thereof,
as respectively indicated by the dotted lines
7—7 and 8—8, whereby end flanges 9—9 and
side flanges 10—10 are formed from each
blank, as indicated in Figs. 1, 3 and 4, so
that when completed there results a dia-
phragm surrounded by and contiguous with
a continuous rim extending at a right angle
to the diaphragm. After so forming the two
parts their respective diaphragms are then
rigidly secured together either by soldering,
riveting or welding, but preferably by elec-
trically welding them at intervals, as indi-
cated by dotted lines at 11—11, or may be
by one or more rivets 12.

By forming a filler or other printers' fur-
niture, as may be, in two parts from sheet
steel, and then securing them together in the
manner above described, it will be readily
observed that the production of fillers and
other printers' furniture is made practical
and possible from sheet steel as the best and
most efficient material for successfully re-
sisting the force of strain from every di-
rection they may be subjected to without the
possibility of the bending of the rim or
separating the two parts, for when properly
joined both lateral and compressive strains
are uniformly distributed simultaneously
throughout the filler in every direction, with
the result that even a single rivet or spot
weld is sufficient to hold the two parts as one
when operatively in use.

While I have shown and described the
embodiment of my invention in a printer's
filler specifically, it should be understood

that my invention includes any and all other forms of printers' furniture and devices capable of being formed of two pieces of sheet steel, the rim of which is continuous and integral with any base support therefor.

Having described my invention, what I claim and desire to secure by Letters Patent is:—

- 10 1. As a new article of manufacture printers' furniture consisting of two pieces of sheet steel, each of which is provided with a continuous jointless rim integrally bent therefrom, and means connecting said pieces together, substantially as described.
- 15 2. As a new article of manufacture printers' furniture consisting of two pieces of sheet steel each of which is provided with a

continuous jointless rim respectively integral therewith, and joined together to form 20 a diaphragm therefor, substantially as described.

3. As a new article of manufacture, printers' furniture consisting of two pieces of sheet steel welded together, each of which 25 is provided with a jointless and integral rim bent therefrom, substantially as described.

In witness whereof I have hereunto set my hand and affixed my seal, this 22nd day 30 of June, A. D. 1911.

JOHN A. FRASER. [L.S.]
